UNITED STATES PATENT OFFICE.

DAVID DAGOBERT GORDON, OF CHICAGO, ILLINOIS.

SWITCHING DEVICE.

1,040,309.

Specification of Letters Patent.

Patented Oct. 8, 1912.

Application filed June 20, 1911. Serial No. 634,214.

To all whom it may concern:

Be it known that I, DAVID DAGOBERT GORDON, a citizen of the United States, residing at Chicago, in the county of Cook and State of Illinois, have invented a certain new and useful Improvement in Switching Devices, of which the following is a full, clear, concise, and exact description, reference being had to the accompanying drawings, forming a part of this specification.

My invention relates to switching devices and more particularly to switching devices for electrical circuits in which movable elements preferably alternately conducting and non-conducting are arranged in association with circuit terminals to thereby effect circuit changes.

My invention is more particularly an improvement over the structure disclosed in my application Serial No. 618,410, filed April 1, 1911. In this said co-pending application I set forth a device of the general character above described, and in my present application I set forth a device of this character in which means are provided whereby the circuit changes in response to the actuations of my device are of the quick acting character so as to avoid the objectionable features of slowly moving contact elements which have a tendency to cause serious arcing disturbances.

My invention furthermore contemplates the provision of a device of this character which may be of the double pole variety.

My invention furthermore has for its object the provision of a plurality of contact terminals with which a contact making element is adapted to be associated, which contact terminals are of such structure that the contact element if not in proper electrical connection with both contact terminals is held away from one contact terminal by the other contact terminal so as to avoid sparking.

I will explain my invention more in detail by reference to the accompanying drawing, illustrating the preferred embodiment thereof, in which:

Figure 1 is a side view of my device, one-half of the inclosing shell being removed; Fig. 2 is a similar view with the operating portion of the device in its operated position; Fig. 3 is a sectional view on lines *a—a* of Fig. 1; Fig. 4 is a view similar to Fig. 1 showing my device adapted for double pole circuit changing work; Fig. 5 is a partial

sectional view on lines *b—b* of Fig. 4, portions however being shown in full more clearly to reveal the structure, and Fig. 6 is a detail view to illustrate the arrangement of the contacting elements.

Referring to the illustration, I set forth a switching device having two inclosing halves 1 and 2, which are held together by means of a bolt or screw indicated in cross section at 3. A circular runway 4 is provided in the members 1 and 2, and is formed by two circular runways semi-circular in cross section formed in these two elements, as will be clearly apparent. A stud 5 forms a central guide within the runway 4. Conducting balls 6 and non-conducting balls 7 are arranged for operation within this runway. These balls are adapted to be propelled about the said runway by means of a push button 8 to be presently explained. Contact springs 9 and 10 are provided in the insulating sections 2 and 1 and are so arranged as to project partially within the runway 4, forming therein dished or saucer like contacting surfaces 11 and 12 respectively. These dished contacting surfaces are for the purpose of maintaining the balls either 6 or 7 between them whenever they are so placed by the push button 8. The contact elements 9 and 10 are held respectively within the sections 2 and 1 by means of screws 13 and 14, which screws project into angle pieces 15 and 16 respectively. These angle pieces 15 and 16 are bent as shown and are provided with screws 17 and 18 to which the outside lead wires for the circuit to be controlled by the switch are to be connected, either one of the balls 6 serving to close this circuit or the balls 7 to maintain it open. The contact surface 11 is smaller in diameter than the contact surface 12 as is more readily apparent from Fig. 6 which is for the purpose of preventing any conducting ball which may have been pushed partly beyond its contact making position through some faulty operation of the push button from falling back against these contacting surfaces, and by being in close association with both of them causing arcing.

It will be seen that one surface 12 being larger than if the ball should fall back it would have to fall back against the contact surface 12 and this would prevent it from reaching the contact surface 11 so that no arc would be established. This however, is

only to guard against a faulty operation which might occur, if for instance any of the parts were broken. The arrangement of these switch elements in this manner has 5 other advantageous features which will be readily apparent to those skilled in the art.

In Fig. 4 I have illustrated that two additional pairs of springs 9 and 10 may be utilized by the indication at 19 of a spring 10 corresponding to the spring 9 whose counterpart would be in the opposite section 1. It will thus be seen that the two wires of the circuit may both be close 15 circuited or open circuited so that the switch structure as shown in Fig. 4 is capable of use for double pole switching purposes.

The prime object of the invention, as before stated, is to secure quick break action 20 of the elements herein as I find that under 25 a great number of conditions a switching device of this character will not operate properly. To accomplish this quick break and quick make feature, I construct the push button 8 as will now be described.

25 A cylindrical groove 20^b is provided in the parts 1 and 2 formed of two semi-circular halves. Within this a plunger 20 is designed to operate. This plunger 20 is hollow and carries a second plunger or piston 30 30 21, both parts being held in their extended position by means of a spring 22. The plunger 21 has a flange 23 and is prevented from leaving the plunger 20 by the shoulder 24, the parts being suitably assembled, by 35 reason of the removable cap 25. A spring 26 resting against a ledge 27 and engaging at its opposite end the plunger 20 normally maintains the plunger in the position shown in Figs. 1 and 4. The plunger 21 is provided with a groove 28, one side of which is formed of an insulating plate 29. This groove 28 is normally engaged by a sliding plate 30 held in its depressed position by 40 means of the spring 31. This spring 31 as stated normally secures the engagement of the groove 28 by the plate 30. A rectangular projection 32 is preferably punched out of the plate 30 and is adapted for engagement by the rim 33 provided at the left hand 45 50 extremity of the plunger 20. Now when the push button 8 is moved toward the left, it will compress both springs 22 and 26 as the plunger or piston 21 is held against movement toward the left by the plate 30, 55 which plate it may be stated slides within a groove 34 provided in the elements 1 and 2. As soon as the rim 33 has reached the projection 32 the plate 30 is moved upwardly against the pressure of the spring 31, thereby releasing the plunger 21 and 60 causing it rapidly and as nearly instantaneously as possible to assume the position shown in Fig. 2. A very sudden acting release on account of the spring action due 65 to the spring 22 and complete operation of

the device must take place after the plunger has once been released. This is of the utmost importance in a device of this kind because without such provisions it will not operate satisfactorily under most conditions. 70 The projection 35 against which the spring 31 rests is formed preferably on the element 2 and projects into the element 1 serving at the same time to aline these elements when putting them together. When the pressure against the cap 25 is released, the spring 26 returns the parts so that they occupy the positions shown in Figs. 1 and 4. It may be added that the plate 30 has a preferably circular aperture 36 through 80 which the plunger 21 may project after the movement of the plate 30 as aforesaid.

The operation will be apparent in that one actuation brings a conducting ball 6 between the springs 9 and 10 to close the circuit therethrough and the next actuation of the plunger brings a non-conducting ball between the springs 9 and 10 to thereby open the circuit between the springs. Reference to Fig. 4 will indicate that two balls 6 may 90 at the same time be in service if the instrument is used for double pole service. Holes 37 and 38 are provided so that the device may be properly mounted. It will be noted that no contact portions are exposed except 95 the screws 17 and 18.

I have herein described of course, merely one embodiment of the invention which is to be taken as illustrative of the same and changes within the scope of the appended 100 claims may be made without departing from the spirit of my invention.

What I therefore claim as new and desire to secure by Letters Patent is:

1. A device of the character described 105 having contact terminals, of contact making balls and insulating balls adapted for alternate interposition between said terminals, a runway for said balls into which said terminals project, and automatically quick 110 acting means for actuating said balls.

2. A device of the character described having contact terminals, of contact making balls and insulating balls adapted for alternate interposition between said terminals, 115 a runway for said balls into which said terminals project, and an automatically quick acting push button for actuating said balls.

3. A device of the character described 120 having contact terminals, a runway into which said terminals project, an individual contact making and an individual insulating element adapted for progressive movement about said runway to alternately close circuit or open circuit through said contact terminals, and automatically quick acting 125 means for actuating said elements.

4. A device of the character described 130 having contact terminals, a runway into

which said terminals project, a contact making and an insulating element adapted for progressive movement about said runway to alternately close circuit or open circuit through said contact terminals, and automatically quick acting means for actuating said elements.

5. A device of the character described having contact terminals, a runway into which said terminals project, a contact making element, and an insulating element adapted for alternate interposition between said terminals and movable progressively forward about said runway, and automatically quick acting means to move said elements about said runway.

6. A device of the character described having contact terminals, of contact making elements, and insulating elements adapted for alternate interposition between said terminals, a runway for said elements about which said elements move progressively forward and into which said terminals project, and automatically quick acting means for actuating said elements. 20
25

In witness whereof, I hereunto subscribe my name this 14th day of June, A. D. 1911.

DAVID DAGOBERT GORDON.
